ERNEST M. GLASGOW, OF PORT CHESTER, NEW YORK, ASSIGNOR TO RUSSELL & STOLL COMPANY, OF NEW YORK, N. Y., A CORPORATION OF NEW YORK.

SAFETY SWITCH.

Application filed February 9, 1924. Serial No. 691,606.

My invention relates to the construction of electric switches of the type wherein the switch itself has a snap action and wherein provision is also made for the substitution of fuses within the enclosure.

The invention relates more particularly to an improved construction of safety switch wherein the switch and the cover are so interlocked that the cover cannot be removed to expose the switch mechanism while the switch is closed and the switch must be thrown to "off" position to permit the cover to be removed while conversely it is necessary to fully restore the cover before the switch can function to close the circuit.

The object of the invention is also to provide an improved construction such that the handle must be manipulated in a direction to open the switch before the cover can be removed and also before it can be restored, the restoration then freeing the switch to permit it to be moved back to closed position.

The special object of this part of the invention is to insure the opening of the switch before the box is opened thereby making the device immune from danger in use under all conditions or in the case through derangement by unwarrantable interference or through accident, the parts within the box should be in a condition which would permit the cover to be removed while the circuit is closed.

A further object of the invention is to insure a condition of safety at the fuse clips before or while the cover is removed so that fuses may be removed or replaced without any danger whatever by reason of the fact that the fuse clips themselves are disconnected both from the line and from the circuit which is made dead by throwing the main switch to "off" position.

My invention consists in the improved constructions of apparatus hereinafter described and illustrated in the accompanying drawings and more particularly specified in the claims.

In the drawings:

Fig. 1 is a plan of the apparatus within the casing, the insulating plate supporting the fuse clips being removed and parts being shown in section on the line 1—1 Fig. 2.

Fig. 2 is a side elevation of the mechanism, the box and supporting plate of insulating material within the same being shown in vertical longitudinal section.

Fig. 3 is an end elevation of the apparatus within the box, said box being shown in vertical cross-section.

Fig. 4 is a plan of the plate of insulating material supporting the fuse clips, the switch contacts and switch blades supported on the under side of said plate being indicated in dotted lines.

Fig. 5 is a vertical section of Fig. 4 on the line 5—5.

Fig. 6 is an elevation of the box in reduced size as ordinarily mounted for use.

1 indicates the switch box, 2 the cover pivoted for instance at 3 on one side and held down by a clamp nut 4 at the other side (see

Figs. 1 and 2). The operating shaft shown at 5 is provided with a handle 6 and may be turned by the latter in either direction, to throw the switch from "on" to "off" or vice versa.

Said shaft is mounted to be capable of turning in suitable bearings consisting for instance of bosses 5' projecting from the inner face of the wall of the casing.

Between said bearings 5' the shaft is mounted and turns in a pair of brackets 5'' which depend from a plate or frame 9' secured to the lower face of an insulating slate or other base 9.

Said base 9 is suitably supported by lugs or other means within the casing at a point below and sufficiently removed from the top edge thereof to afford space for the fuse and

fuse clips supported directly thereon and carries on its inner face all of the switch contacts of the snap switch together with the switch blades or similar members co-operating therewith and likewise the snap switch mechanism to be presently described.

The switch arm or arms supporting the blades of the switch consist preferably of a pair of arms 11 suitably fulcrumed to be

capable of turning independently of the handle-actuated shaft 5. In the present instance said arms are, for compactness and simplicity of structure, fulcrumed on the shaft 5 itself between the brackets 5'' and said arms are connected by a cross member or rod 11' to insure the rigidity of the switch arm thus constructed.

The switch blades of any desired number, are indicated at 7. These switch blades operate in pairs, (one pair for each pole of the circuit) to make and break a connection between one side of the main line and the corresponding side of a local or service line and each member of a pair is moved into and out

85

of connection with a pair of contacts to bridge the same and to break connection of a fuse with both the main and service line as will be more particularly hereinafter described. 5 These are bolted or secured in any other suitable manner to the sides of the arm 11 and are insulated from one another and from the bolts or studs supporting the same in the well known manner by bushings, disks and spacers 10 or by other suitable means. The contacts with pairs of which each one of a pair of blades co-operate to open and close the circuit by bridging or opening a bridge between a pair of contacts at both ends of the bridge 15 are indicated at 8 and each contact comprises preferably a pair of springs which project from a block of metal properly secured to the under side of the insulating plate 9 so that the pairs of springs will project inwardly from said base. The switch blades 20 enter in the usual manner between the pairs of springs 8 to close the circuit by bridging the members of a pair of springs. These members 8 and 7 act after the manner of the 25 knife blades and spring contacts of the ordinary knife switch.

Pairs of springs 8' one pair for each pole of the circuit are mounted upon and project outwardly from the base 9 and constitute clips 30 for the fuses 8''. These clips 8' are suitably connected with the bases of the double contacts 8, as will be presently described, and in such manner that when the switch is operated to dis-connect the service or local line from the main line, both fuse terminals will be also disconnected from said lines so that the fuses may be then removed and a new fuse substituted without danger of shock from leakage back from the local or service line 40 in case the service line may have become crossed with some other line or circuit and also with the obvious effect of protection from shock from the main line.

Also, as will be seen, all of the switch terminals are effectively shielded from accidental contact by reason of the fact that they project from the under side only of the insulating plate 9 and are not in any manner exposed when the cover 2 of the box is removed for the purpose of substituting a fuse. 50

From the shaft 5 projects an arm 12 keyed to the shaft 5 and pivotally connected to or linked up with a link 13 the pivotal connection or pivot pin being extended laterally as indicated at 13'. (See Fig. 1). The link 13 terminates in or carries a cross pin 14 which engages slots 15 in the switch arms 11. These slots 15 are elongated in a direction to permit limited lost motion of the link 13 and operating shaft 5 when the latter is turned by the operating handle. The pin 14 is coupled to the switch arm by engagement with the sides of the slot and acts as a dog to hold the switch arm 11 from movement under the influence of the snap action spring while the

spring is being put under tension as will be presently described, said dog for this purpose co-operating with a suitable stop from which it is disengaged under the action of the turning movement of the shaft 5 in winding 70 up the snap action spring.

The stop device consists of a pair of step latches 19, 19' one of which holds the dog and switch arms 11 temporarily when the shaft 12 is turned to open the switch, while 75 the other acts on the reverse movement whereby the switch is closed. The snap action spring is indicated at 16 and is wound around the main operating shaft 5. Said spring is normally without tension but movement of 80 the shaft in either direction places it under tension. The free extremities of the spring are operatively connected respectively with the switch arms 11 in any desired way to act respectively on the same in opposite directions. Thus, for instance, one free end thereof may hook on top of one of the pairs of switch arms 11 to move them in one direction while the other free end hooks underneath one of said arms and is thereby operatively 85 connected with the compound switch arm to actuate said arm in the opposite direction.

The winding up action of the spring is secured by engagement of the ends of the pin 13' therewith. One end of said pin engages the 90 spring on its upper side and the other engages it on its under side. As will be obvious, the turning of the arm 12 secured to the shaft 5 in a downward direction, for instance, will wind up one end of the spring by engagement 95 of one end of pin 13' with the top side of the spring, while the other end of the spring being hooked on top of the switch arm will apply the snap spring action to the arm 11 when the arm is released by disengagement of the 100 dog from the stop or catch with which it is engaged until withdrawn from engagement by the movement thereof in the slot inward toward the shaft 5 by the action of the link 13. The other end of pin 13' engaging under the 105 opposite end of the spring will, on turning of the shaft in the opposite direction, wind up said end while the opposite end which hooks under the arm will throw it in the opposite direction when the arm is released by disengagement 110 of the pin or dog 14 from the latch or stop which normally opposes the movement until, in the winding up movement of the shaft, said dog has been drawn inward toward the shaft away from engagement with 115 said stop or latch. The stop or latch devices engaged by the dog 14 are two in number and are preferably constructed and mounted as follows:—

A fixed support for the same comprises 120 preferably the fixed bracket or yoke 17 which may be cast in one piece with or properly secured to the supporting plate 9' and projects inwardly from the insulating plate 9, as 125 shown. These latches or stops consist of a 130

pair of shouldered plates 19, 19', the former of which is pivotally supported between the arms of the yoke or bracket 17 near the lower end thereof, while the other plate 19' is 5 mounted on a pivot or pivotal support extending between the arms of the bracket near the upper end thereof, as shown clearly in Figs. 2 and 3. The plates 19, 19' are adapted to swing freely and independently of one another in said fixed bracket or yoke 17 and are connected to one another by a spring 18 which normally tends to project the latches into position so that the dog 14 will engage and be locked by one or the other of them as shown in 10 the case of latch 19. One of said latches, to wit, the latch 19, locks the dog 14 while the spring is being wound up preparatory to a throwing of the switch to open position, while the other latch or stop 19' similarly locks the 15 dog and switch arm during the winding up action of the spring by the shaft 5 preparatory to the movement of the switch to closed position. A pin 20 supported in the yoke 17 passes transversely through an opening in the 20 latches 19, 19' and serves as a stop pin to limit their motion under the action of the spring 18. When the dog is disengaged from the shoulder of the latch or stop by which it is locked, it passes freely over the inclined side of the 25 other latch until it reaches position to permit the latch to spring out so that the shoulder thereof will pass over the dog 14 and the latter will be thereafter locked by said latch until the dog is again withdrawn from locking 30 position.

The drawing Fig. 2 shows the switch in closed position. The turning of the shaft handle 6 to throw the switch arm to "off" position winds up the snap action spring 16 and 35 finally withdraws the dog 14 from locking position on the shoulder of latch 19. Thereupon the switch arm is thrown by the action of the spring which is being placed under tension while winding up one end thereof. 40 The switch now assumes the "off" position indicated in dotted lines and the dog 14 is locked under the shoulder of the other latch. A reverse movement of the shaft 5 by the handle 6 to close the switch now winds up the opposite 45 end of the spring until, during the winding movement, the dog has been pulled in toward the shaft 5 sufficiently to be disengaged from the shoulder of the second latch 19' whereupon the spring, by engaging under the 50 switch arm by its opposite hooked end, throws the arm back to the closed position.

The interlocking of the cover and the switch is accomplished by the following devices. 21 is a pivoted catch pivotally mounted 55 on and depending from the casting or plate 9' secured to the insulating plate 9. A spring 21' tends to move it in the direction of the arrow (see Fig. 2). The cross-bar or member 11' of the switch arm moves in the vertical, 60 slightly curved slot in the catch 21 and is

adapted to engage with a shoulder 23 of said catch when the switch arm is in the open position and the catch 21 has been moved over by the spring 21' into the position indicated in dotted lines. In this position of the parts the 70 switch is locked in open or "off" position. The catch 21 is normally retained, however, in inoperative relation to the switch arm by a lug 25 carried by the cover and engaging the catch 21 to hold it over in the position indicated in full lines while the cover is in closed position, thereby permitting the switch to be operated as a snap switch in the usual way so long as the cover is down. The lug 25 extends 75 downwardly from the cover to an opening in plate 9 and then engages, by means of an insulating projection 26, with an upwardly extending projection 27 carried by the pivoted catch 21 and extending into the opening in the plate 9 as clearly shown. When the cover is 80 thrown up, after throwing the switch to open position, the catch 21 is released and assumes 85 position for locking the switch in open or "off" position.

The cover cannot be moved to expose the 90 fuses or the interior mechanism of the box until after the switch has been thrown to "off" position or position indicated in dotted lines. The means for securing this result consist of a hook or catch 28 extending from the arm 12 95 of the operating shaft 5 and interlocking with a bar 29 extending downwardly from the cover and having an opening at its lower end through which the hook passes. Only when the switch is thrown down to "off" position 100 and slightly beyond can the hook 28 be moved sufficiently to release the bar 29 and thus permit the cover to be raised. This result is attained by making the hook 28 so long that even after the switch has been thrown 105 to the position indicated in dotted lines in Fig. 2, the end of the hook will not be fully withdrawn from the aligning opening in the locking bar 29. That is to say, if the switch be snapped to "off" position by operating the 110 handle 6, the cover 2 will be still locked down unless a further movement is given to the operating handle and shaft, resulting in turning the hook 28 sufficiently to withdraw its 115 end fully from the opening in the bar 29. This movement is given simply by pressing the handle in the general direction of the "off" movement to position beyond the position in which the handle is left for "off" position of the switch. This further movement 120 is permitted without obstruction from the switch arm which at such time is in "off" position because the arm 12 and connected parts, being capable of lost motion with respect to the switch arm as already described, may 125 make the further required movement for effecting full release between 28 and 29 without interference from the position of the switch arm which has completed its action under the snapping effect of the spring 16. 130

When the handle 6 is pressed in the direction described as "off" the box may be opened by lifting the cover. This insures a manipulation of the switch to "off" position before the box can be opened. Obviously when the pressure is removed and the box cover is up the hook 28 will return a slight distance toward normal position but will then be in position to be engaged by the end of the bar 29. This will prevent the cover from being thrown down fully should the attempt be made to close the box without throwing the switch to "off" position, and also results in holding the cover up sufficiently to prevent the cover from releasing the catch 21 which it must do in order that the switch may be snapped back to closed position. Hence, when the box is open it is likewise necessary to throw the handle 6 to full "off" position or in a direction to open the switch before the cover can be thrown down to fully closed position which is the position it must reach before it will unlock the switch arm from the restraint of the catch 21.

Secured in the bottom of the box 1 is a slate or other insulating base 30 on which are mounted connecting blocks 31, 31', for attachment of the main line or service or local cables. From these blocks extend the interior cables 32, 32' whose free ends beneath the slate base 9 are fastened to the conducting blocks which carry respectively the various line and service contacts 8 of the knife switch, said blocks being attached to the under side of the slate base 9 and having the spring contacts 8 projecting therefrom downwardly away from the base. One of the two openings in the end of the box through which the main line and local cables may be introduced for attachment to the connecting blocks 31, 31' is indicated at 33. For convenience of attachment, the connecting cables 32 within the box are used as the main line connecting cables and the cables 32' as connecting cables from the local or service line, although a reverse arrangement might be employed using the connections 32 as the local or service line connections. Assuming that the latter are used as the main line connections and the cables 32' as the service line connections, the connection to the various switch contacts may be made by attachment of the cable ends to the blocks carrying said switch contacts in the order or arrangement indicated in Fig. 4 where the various switch contacts and blades beneath the slate base 9 are indicated in dotted lines. Two fuse clips 8' at one end of the slate base and rising therefrom are located opposite one of the two contacts 8 at the same end of the base and are in immediate connection therewith through the screws or bolts 34 which fasten the base blocks for said contacts and clips to the opposite face respectively of the slate base 9. At the other end of the slate base 9 fuse clips 8' are fastened directly

to the upper face of the base by the screws 34'. Connection is established between them and the contacts 8 with which the blades 7 cooperate to close the connection from the main line terminal switch contacts 8, by means of straps 35 fastened by means of the screws 34' under the block from which the fuse clip rises, and at the other end fastened down upon the upper face of the block by screws 36 which extends through the base and fastens the local or service line switch contact 8 to the under surface of the slate base.

As will be seen by reference particularly to Fig. 4, two pairs of blades are employed, one pair for each pole of the circuit, and each member of a pair is moved bodily by the action of the arm 11 into and out of bridging relation with a pair of contacts 8 one member of one of said pairs of contacts being connected beneath the insulating plate or base 9 with a local or service connecting wire or cable 32' while the other member of said pair of contacts is directly joined by means of a screw or bolt 34 with one of the pair of fuse clips 8' used for the corresponding pole of the circuit. The other member 7 of the pair of blades now referred to is correspondingly and at the same time brought into and out of bridging relation with another pair of contacts 8 one joined beneath the plate or base 9 with the main line connecting wire or cable 32 while the other one of the pair of contacts with which said plate cooperates is suitably joined with the base of the other member 8' of the pair of fuse clips referred to.

The connection thus established through the switch contacts, the blades, fuse clips and the fuses may be readily traced by the arrows and the result of the arrangement is that when the blades of a pair sever connection each with its pair of contacts 8, not only is the connection between the main line and the local or service line interrupted at two points but the fuse clips 8' are disconnected from both the main line and the service or local line thereby permitting the fuses to be substituted without danger. Moreover, inasmuch as all the main line and service line contacts of the switch and the connections thereto are arranged on the under side of the base 9 and project downwardly therefrom there is no possibility of contact therewith by the hand of the operator.

The particular construction of snap switch or snap switch action hereinbefore described forms the subject of claims in my application filed Oct. 23, 1924, as a division hereof, Serial No. 745,270.

What I claim as my invention is:—

1. In a safety switch, the combination of an operating shaft, a switch arm, a hook carried by and movable with said shaft, a cover, a locking bar fixedly mounted on said cover and engaged by said hook and a snap action dog connected with the arm by a lost motion

whereby further movement in the direction for opening the switch may be imparted to the hook after the switch arm has come to rest in the "off" position to thereby move 5 the hook out of engagement with said locking bar.

2. In a safety switch, the combination of a switch arm, an operating shaft operatively connected with the arm for throwing the same 10 to "off" position, said shaft having a lost motion with respect to the arm and interlocking means between the shaft and cover comprising a member carried by and moving with said operating shaft and a cooperating member fixed in position on the cover, said members interlocking directly with one another 15 in the normal "off" position of the operating shaft and being adapted to be disengaged by moving the operating shaft beyond its normal 20 "off" position.

3. In a safety switch, a switch operating member, a casing, a cover for said casing, latching means for maintaining said cover

latched in its closed position in both the closed and open positions of said switch, yieldable 25 means permitting the movement of said switch operating member to a point beyond the normal open condition of said switch for releasing said cover from said latching means.

4. In a safety switch, the combination of 30 an operating shaft, a switch arm, latching means movable with said switch arm, a cover, cooperating latching means movable with said cover, movable switch blades, connecting means pivotally connected to said shaft and 35 movably mounted on said switch blades, cooperating locking dogs for securing said switch blades from movement in the opposite direction from either open or closed position, said switch blades being released from said 40 locking dogs by the movement of said connecting means relatively to said switch blades.

Signed at New York, in the county of New York and State of New York, this 8th day of February A. D. 1924.

ERNEST M. GLASGOW.
